UNITED STATES PATENT OFFICE.

WILLIAM E. GRAY, OF CHICAGO, ILLINOIS.

ELECTRICAL VIBRATOR.

Application filed September 21, 1925. Serial No. 57,563.

My invention relates to new and useful improvements in electrical vibrators, and has for its object the provision of an improved construction of this character which is capable of economical manufacture and is highly efficient in use.

Other objects will appear hereinafter.

The invention consists in the combinations and arrangements of parts hereinafter described and claimed.

The invention will be best understood by reference to the accompanying drawings forming a part of this specification, and in which,

15 Fig. 1 is a side view of an electrical vibrator embodying the invention;

Fig. 2 is a bottom plan view corresponding with Fig. 1;

Fig. 3 is a transverse section taken on line 20 3—3 of Fig. 2;

Fig. 4 is a transverse section taken through the forward end of the vibrator;

Fig. 5 is a section taken on line 5—5 of Fig. 4;

25 Fig. 6 a longitudinal section of the vibrator;

Fig. 7 a section at right angles of Fig. 6;

Fig. 8 a section taken on line 8—8 of Fig. 7; and

30 Fig. 9 a front end view of the vibrator.

The preferred form of construction as illustrated in the drawings comprises a suitable casing 10 having a removable cover 11, said casing being of an elongated rectangular shape and adapted and arranged to constitute a hollow handle. Arranged in the casing 10 is an electro-magnet 12 arranged to be supplied with alternating current through feed wires 13 through a leaf spring switch

40 14 carrying a button or flange 15 projecting laterally through the side wall of casing 10 in position to be pressed by the thumb of the operator to close the circuit through the electro-magnet 12 when desired. Cooperating

45 with the magnet 12 is a vibrating armature 16 pivoted at 17 on a mounting block 18 which in turn is pivoted at 19 in the casing 10. An adjusting screw 20 is threaded in the block 18 and swiveled in the side wall 50 of casing 10, a compression spring 21 being interposed between the block 18 and said side wall. By this arrangement it will be noted that the end of the armature 16 may be nicely adjusted with reference to the magnet 12.

55 The armature 16 is operatively connected by stud 22 to the central portion of the leaf

spring 23, which is mounted at one end on a supporting post 24 secured to the side wall of casing 10. The other end of spring 23 is attached to adjustable block 25 slideable in 60 the socket 26 on the side wall of casing 10. The block 25 is threaded on an adjusting screw 27 and cooperates with the compression spring 28 whereby the tension of the leaf spring 23 may be nicely adjusted, as desired to regulate the operation of armature 16.

The armature 16 is provided with a laterally turned end 29 carrying a pin 30 projecting through a slot 31 in a partition wall 32 at the forward end of the casing 10. The pin 30 engages a slot 33 in the upper end of an oscillatory lever 34 pivoted at 35 to the partition wall 32. The casing 10 is provided at its forward end with a lateral extension 36 and the partition wall 32 forms a transverse chamber extending across the forward end of said casing. The transverse chamber thus formed is provided with a removable cover 37 giving access to the parts within. A supporting frame 38 is arranged in said transverse chamber and a block 39 is arranged to slide in suitable guides 40 on the bottom of said frame. An arm 41 is rockingly connected with the block 39, as shown, and projects upwardly through suitable slots in the bottom of frame 38. At its upper end arm 41 carries a stem 42 fitting loosely in a socket 43 formed in the lower end of lever 34, and whereby said arm 41 slidably engages said lever. By this arrangement the vibrations of the armature 16 are caused to oscillate the lever 34, the effect of said vibrations being multiplied and transmitted to the block 39 causing said block 39 to reciprocate 80 laterally in its guides. The block 39 is provided with a downwardly extending threaded socket 44 projecting through a slot in the bottom of the chamber 36 and adapted and arranged to receive and engage a threaded

85 stem 45 on a member 46 as shown. The member 46 may be any suitable or desired vibrator appliance, such as a rubber massage contact piece, an eraser or other desired appliance which it is desired to vibrate at high speed. In this way a very simple and effective device for vibrating various appliances is provided which is capable of economical manufacture and is highly efficient in use.

100 While I have illustrated and described the preferred form of construction for carrying

my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A device of the class described comprising an electro-magnet; a vibrating armature cooperating therewith; a slide block arranged in guides; means for mounting various reciprocatory appliances on said block; and an operative connection between said block and said armature, substantially as described.
2. A device of the class described comprising an electro-magnet; a vibrating armature cooperating therewith; an oscillatory lever having one end operatively connected with said armature; a slide block arranged in guides; means for mounting various reciprocatory appliances on said block; and an operative connection between said block and lever, substantially as described.
3. A device of the class described comprising an electro-magnet; a vibrating armature cooperating therewith; an oscillatory lever having one end operatively connected with said armature; a slide block arranged in guides; means for mounting various reciprocatory appliances on said block; and an arm rockingly engaging said block and slidably engaging said lever, substantially as described.
4. A device of the class described comprising an electro-magnet; a vibrating armature cooperating therewith; an oscillatory lever having one end operatively connected with said armature; a slide block arranged in guides; means for mounting various reciprocatory appliances on said block; an arm rockingly engaging said block; and a stem on said arm, there being a socket in the other end of said lever into which said stem fits loosely, substantially as described.
5. A device of the class described comprising an electro-magnet; a vibrating armature cooperating therewith; an oscillatory lever; a slot and pin connection between one end of said lever and said armature; a slide block arranged in guides; a threaded socket on said slide block arranged to receive various appliances; an arm rockingly engaging said block; and a stem on said arm, there being a socket in the other end of said lever into which said stem fits loosely, substantially as described.
6. A device of the class described comprising a casing shaped and arranged to con-
- stitute a hollow handle; a removable cover for said casing; an electro-magnet arranged in said casing; a vibrating spring-held armature in said casing and cooperating with said magnet; a lateral extension to said casing and a partition wall forming a chamber extending laterally across the end of said casing; a pin mounted on the end of said armature and projecting into said transverse chamber, there being a transverse slot in said partition to accommodate such pin; an oscillatory lever mounted in said transverse chamber and having a slot at its upper end engaging said pin; and a reciprocatory appliance operatively connected with the lower end of said lever, substantially as described.
7. A device of the class described comprising a casing shaped and arranged to constitute a hollow handle; a removable cover for said casing; an electro-magnet arranged in said casing; a vibrating spring-held armature in said casing and cooperating with said magnet; a lateral extension to said casing and a partition wall forming a chamber extending laterally across the end of said casing; a pin mounted on the end of said armature and projecting into said transverse chamber, there being a transverse slot in said partition to accommodate such pin; an oscillatory lever having a slot at its upper end engaging said pin; a slide block arranged in guides on the bottom of said transverse chamber; a threaded socket on the bottom of said block for receiving various appliances; and an arm rockingly engaging said block and slidably engaging said lever, substantially as described.
8. A device of the class described comprising a casing shaped and arranged to constitute a hollow handle; a removable cover for said casing; an electro-magnet arranged in said casing; a vibrating spring-held armature in said casing and cooperating with said magnet; a lateral extension to said casing and a partition wall forming a chamber extending laterally across the end of said casing; a pin mounted on the end of said armature and projecting into said transverse chamber, there being a transverse slot in said partition to accommodate said pin; an oscillatory lever having a slot at its upper end engaging said pin; a slide block arranged in guides on the bottom of said transverse chamber; a threaded socket on the bottom of said block for receiving various appliances; an arm rockingly engaging said block; and a stem on said arm, there being a socket in the other end of said lever into which stem fits loosely, substantially as described.

In testimony whereof, I have signed my name to this specification.

WILLIAM E. GRAY.
